(57) **CLAIM**

The ornamental design for a package for nail polish bottles, as shown and described.

DESCRIPTION

FIG. 1 is a top perspective view of a first embodiment of our new package for nail polish bottles design;

FIG. 2 is a bottom perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top view thereof;

FIG. 8 is a bottom view thereof;

FIG. 9 is an exploded perspective view thereof, in a first arrangement; and

FIG. 10 is an exploded perspective view thereof, in a second arrangement.

FIG. 11 is a top perspective view of a second embodiment of our new package for nail polish bottles design;

FIG. 12 is a bottom perspective view thereof;

FIG. 13 is a front elevation view thereof;

FIG. 14 is a right side elevation view thereof;

FIG. 15 is a rear elevation view thereof;

FIG. 16 is a left side elevation view thereof;

FIG. 17 is a top view thereof;

FIG. 18 is a bottom view thereof;

FIG. 19 is an exploded perspective view thereof, in a first arrangement; and,

FIG. 20 is an exploded perspective view thereof, in a second arrangement.

The broken lines shown in the drawings depict portions of the package for nail polish bottles that form no part of the claimed design.
